UNITED STATES PATENT OFFICE.

WILLIS H. GUNDRUM, OF DENVER, COLORADO.

AUTOMOBILE-ENGINE VENTILATOR.

1,251,223.

Specification of Letters Patent. Patented Dec. 25, 1917.

Application filed July 14, 1914. Serial No. 851,010.

To all whom it may concern:

Be it known that I, WILLIS H. GUNDRUM, a citizen of the United States, residing in the city and county of Denver and State of Colorado, have invented certain new and useful Improvements in Automobile-Engine Ventilators; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in means for ventilating the engines of automobiles. My improvement embodies adjustable devices whereby the hood of the engine may be supported in such a manner as to allow the free circulation of air from the front and upper part of the hood downwardly, the air passing out underneath the opposite sides of the hood which are supported for the purpose. In actual practice, I have found this invention of very great value, particularly in hot weather. It is, of course, during the warm season that the over-heating of automobile engines is most troublesome, oftentimes necessitating stops for a water supply a number of times during a trip of ordinary length. However, through the medium of my simple improvement whereby the opposite sides of the hood are supported for ventilating purposes, I have found that the difficulty heretofore outlined is practically obviated. By having the hood supported in such a manner that it is open at the top and in front and also at the bottom, provision is made for a strong draft of air during the movement of the machine, into the upper part of the space within which the engine is located and out below or underneath the sides of the hood. This draft of air has remarkable effect in cooling the engine and maintaining the water employed for the purpose at a reasonably low temperature, whereby boiling is practically prevented.

In my improvement, I employ adjustable blocks which, when the hood is in its normal position, are spring actuated to maintain the

hood in the closed position by downward pressure. Again, when the sides of the hood are raised, the same devices serve to support these sides securely in the raised position, thus preventing rattling or any undue vibration.

In the embodiment of the invention illustrated in the drawing, I employ two blocks or supporting devices in connection with each side of the hood. A rod passes through each of these blocks and is vertically movable therein, a spring acts upon each rod to normally maintain the latter at its downward limit of movement, the upper extremity of the rod being so constructed that it acts upon the top of the block to press the latter downwardly in accordance with the tension of the spring. When the hood is in its normal position, the lower part of each of the blocks acts upon the rib at the lower extremity of each side of the hood and holds the latter tightly in place; while when the sides of the hood are raised, this same rib is engaged and supported by the upper extremities of the blocks, the latter being reversible for the purpose.

Having briefly outlined my improved construction, I will proceed to describe the same in detail, reference being made to the accompanying drawing, in which is illustrated an embodiment thereof. In this drawing—

Figure 1 is a perspective view of the hood extremity of an automobile, showing the hood adjusted for ventilating purposes.

Fig. 2 is a vertical section taken through one of the adjustable blocks of my device and its connections, the same being shown in operative relation with one side of the hood, the latter being in its normal position.

Fig. 3 is a similar view showing the adjustable block in elevation and adjusted to permit the raising or lowering of the adjacent side of the hood.

Fig. 4 is a view similar to Fig. 2 but showing the block in the reversed position or in the position for supporting the adjacent side of the hood in the raised position for ventilating purposes.

Fig. 5 is a side elevation of the forward

extremity of an automobile equipped with my improvement.

Fig. 6 is a similar view showing a slightly modified form of machine.

5 The same reference characters indicate the same parts in all the views.

Let the numeral 5 designate the hood of an automobile engine, the same consisting of two members 6 hinged at the top as 10 shown at 7. Each member 6 of the hood is further hinged at the corner as shown at 8, whereby the top and bottom parts 9 and 10 are hingedly connected. By virtue of this construction, it becomes practicable to raise 15 the opposite sides of the hood in such a manner as to form openings 2 at the top and openings 3 at the bottom for ventilating purposes (see Fig. 1). The lower extremity of each side member 10 of the hood as illustrated 20 in the drawing is provided with a rib 13 which, when the sides of the hood are in their normal or lower position, rests upon the inner portion of a horizontal ledge 14 with which the front part of the automobile 25 frame work is provided.

Mounted upon this ledge on each side of the machine is a plate 15 which is secured to the ledge 14 by means of screws 16 or other suitable fastening devices. This plate constitutes 30 a part of my improvement, and is centrally provided with a sleeve 17 which has a relatively long upwardly projecting member 18 and a short depending member 19. The upper part of this sleeve passes 35 through an opening 20 formed in the bottom part 21 of a hollow block 22, which, as illustrated in the drawing, is approximately rectangular in shape and provided at its upper extremity with an opening 23. Through the opening 23 and the sleeve 17, a 40 rod 24 passes. This rod also extends through an opening 25 formed in the upper part of a channel-shaped bar 26 forming a part of the frame work of the machine. The lower 45 portion 29 of this rod projects into the space 28 of the channel bar and its lower extremity is equipped with a stop 27 which is held in place on the rod by a pin 30 passed transversely through the rod's lower extremity. This stop 27 is circumferentially recessed at 50 its upper extremity as shown at 31, to form a seat for the lower extremity of a spiral spring 32, which surrounds the lower part 29 of the rod, its upper extremity bearing 55 against the under surface of the upper flange of the channel bar.

The upper portion of this rod extends 60 above the top part 33 of the block and as illustrated in the drawing, is formed into an eye 34 which is relatively large to facilitate hand manipulation. It will be understood that the upper extremity of the rod may be of any other suitable or desired shape. Between the eye 34 of the rod and

the upper part 33 of the block, a clamping plate 35 is located. This plate is provided with an opening 36 through which the rod passes, the plate being secured to the rod and consequently, movable therewith. The tension of the spring 32 normally acts upon the rod to cause the plate 35 of the latter to press downwardly on the block, whereby the plate is normally held in yielding contact with the upper extremity of the block. The outer portion of this plate is slightly hood-shaped as shown at 37, whereby a curved recess 38 is formed coöperating with a similar recess 39 formed in the upper part of the block, to engage the rib 13 of the hood in coöperative relation when the adjacent 75 side of the hood is raised for ventilating purposes (see Figs. 1 and 4).

The opposite diagonal corner 40 of the block (considered with reference to the recess 39) is exteriorly recessed as shown at 41 to fit the rib 13 of the hood when the adjacent side of the latter is in the normal or lowermost position.

As illustrated in the drawing, each block 22 is tilted whereby one side of its lower 90 extremity is normally slightly raised from the upper surface of the plate 15, while the opposite corner rests upon this plate. Again, by virtue of this tilted position, the openings 20 and 23 in the opposite extremity of 95 the block are arranged near opposite diagonal corners. This peculiar construction and arrangement of the block is believed to be the best form or embodiment of the invention, though it must be understood that the 100 invention is not limited to these details of construction, as any suitable or desirable form of adjustable supporting block adapted to perform the desired function may be employed without departing from the spirit 105 of the invention. For instance, instead of making these blocks hollow, they could, of course, be made solid, but this would increase the quantity of material required and consequently, add to the expense of construction without in any way increasing the efficiency of the device. Again, the position of the blocks could be different, if desired, or so arranged that the rods could pass centrally rather than diagonally therethrough, 110 but as above indicated, the embodiment of the invention illustrated in the drawing is believed preferable, at least so far as my experiments and demonstrations have gone. In other words, the construction disclosed 115 has proven itself entirely satisfactory in actual practice, but for obvious reasons, I do not desire or intend to limit the invention to the precise construction disclosed or any specific form so far as details are concerned, the 120 only desideratum being that the blocks shall be adjustable and of such construction as to perform the function herein outlined.

- As illustrated in the drawing, it is intended to employ two blocks 22 on each side of the hood. Normally, or when the sides of the hood are in their normal or lowermost position, the corner 40 of each block rests upon the rib 13 of the adjacent side member 10 of the hood, whereby the latter is securely held in the closed position against vibration of undue movement.
- When it is desired to raise the opposite sides of the hood to the position illustrated in Fig. 1, the rod 24 of each device is raised to release the block, whereby the latter may be turned to the position illustrated in Fig. 3. It should be explained that the depth or thickness of the block horizontally is less on the surface exposed in Fig. 3 than is the thickness measured on the same line when the block is in the position shown in Figs. 2 and 4. In other words, when the block is adjusted as shown in Fig. 3, its thickness in a direction transverse to the length of the machine, is less than when in the other position. Consequently, when the block is adjusted as shown in Fig. 3, there is sufficient space between it and the adjacent side member 10 of the hood to permit the raising of the latter to the position shown in Figs. 1 and 4. When the side of the hood is so raised, each block is further adjusted to bring it into the position shown in Fig. 4, the clamping plate 35 being held by the proper manipulation of the rod, out of the way to allow the rib 13 to rest in the recess 39 of the block, after which the plate 35 is adjusted through the medium of the rod to engage the rib 13 from above. The rod 34 is then released and the action of the spring 32 causes the plate 35 to press downwardly on the rib, whereby the plate is held in co-operative relation with the block for maintaining the side of the hood in the raised position.
- While, as illustrated in the drawing, it is the intention to employ two of these blocks on each side of the hood, it must be understood that a single block may be employed, or even a greater number than two, if it should be deemed necessary or desirable.
- From the foregoing explanation, it will be understood that when it is desired to lower the sides of the hood from the position shown in Fig. 1 to that shown in Figs. 2 and 3, the rod 24 of each block will be raised and the blocks turned to the position shown in Fig. 3. The sides of the hood then move downwardly to their normal position, after which the blocks may be adjusted as shown in Fig. 2.
- Attention is called to the fact that the air enters the openings 2 in front of the hood. A portion of this air passes out through similar openings 45 at the rear of the upper
- part of the hood (see Fig. 5) and another 65 portion downwardly and out through the rear part 46 of the opening below the hood, as indicated by the arrows in each instance. Again, it is found in practice that the air enters the rear part 47 of each opening 3 70 below the rib 13 of the hood, when the latter is raised.
- In the form of construction shown in Fig. 6, the portion 48 of the machine forward of the dash board 49 slopes downwardly from 75 the dash board, thus facilitating the escape of air through the openings 45 at the rear of the hood, when the latter is raised as shown in Figs. 5 and 6.
- By virtue of the position in which the 80 hood is held and maintained when its opposite sides are raised for ventilating purposes, the cool or atmospheric air is brought in direct contact with the engine and caused to mingle with the hot air resulting from the 85 radiated heat, and as the air which enters the hood or the space inclosed thereby in which the engine is located, passes quickly through the hood and out of the latter from the space or chamber at both the top and 90 bottom of the hood, it is evident that the heat which otherwise would be confined, is carried away and the temperature of the engine so reduced as to prevent the undue heating of the water, as heretofore stated. 95
- Attention is called to the fact that where my improvement is employed, the front part of the bottom of the body of the machine is kept cool, making the machine much more comfortable than where my improved venti- 100 lating apparatus is not employed.
- Having thus described my invention, what I claim is,—
1. The combination with the hood of an automobile engine, of a block mounted adjacent the hood and provided with an opening, a spring actuated rod passing through the opening in the block and permitting the adjustment of the latter for supporting and securing purposes. 105
  2. The combination with the hood of an automobile engine, of a block mounted adjacent the hood and provided with an opening, a spring actuated rod passing through the opening in the block and permitting the adjustment of the latter for supporting and securing purposes, the upper extremity of the rod being provided with a clamping plate having an opening through which the rod also passes. 110
  3. The combination with the hood of an automobile engine, of a block mounted adjacent the hood and provided with an opening, a spring actuated rod passing through the opening in the block, the upper extremity 115 of the block being equipped for supporting the hood in the open position.
  4. The combination with the hood of an

automobile engine, of a block mounted adjacent the hood and provided with an opening, a spring actuated rod passing through the opening in the block, the upper extremity 5 of the block being equipped for supporting the hood in the open position, while the lower extremity is fashioned to engage the lower part of the hood in securing relation.

5. The combination with the hood of an 10 automobile engine, of a yieldingly retained block mounted adjacent the hood and adjustable to bring its upper extremity into and out of the path of the side of the hood, as the latter is raised and lowered.

15. 6. The combination with the hood of an automobile engine, of a perforated block, a rod passing therethrough and movable therein, the rod being under spring tension and acting on the block to hold the latter in 20 proper position for supporting or securing purposes.

7. The combination with the hood of an automobile, of a block of rectangular contour and a spring actuated rod passing diagonally therethrough, the block being loose on 25 the rod and adjustable for hood supporting and securing purposes.

8. The combination with the hood of an automobile engine, of a spring actuated rod 30 mounted on the frame of the machine adjacent the hood, a block perforated to receive the rod, the block being loose on the rod and adjustable to bring its upper part into and out of the path of the rod as the latter is 35 raised and lowered.

9. The combination with the hood of an automobile engine, of a rod vertically movable in an opening formed in the frame, a spiral spring surrounding the rod and acting 40 thereon to draw it downwardly, a block loose on the rod and adjustable for hood supporting and securing purposes, the rod having a shoulder acting on the block to maintain the latter in co-operative relation 45 with the hood.

10. The combination with the hood of an automobile engine, of a rod engaging an opening formed in the frame work, a spring surrounding the lower extremity of the rod 50 and equipped at its lower end with a stop which one extremity of the spring engages, the opposite extremity of the spring engaging the frame work of the machine, a block perforated to receive the rod which extends above the upper extremity of the block, the block being of rectangular shape and the opening for the rod at the top and bottom being near the opposite sides of the block.

11. The combination with the hood of an 60 automobile engine, of a spring actuated rod mounted on the frame work, a block perforated to receive the rod, the block being of rectangular shape and the rod being arranged in non-parallel relation with the

opposite sides of the block, the upper portion of the rod having a shoulder adapted to engage the block for the purpose set forth. 65

12. The combination with the hood of an automobile engine, of a block mounted adjacent the hood and provided with an opening, 70 a spring actuated rod passing through the opening of the block and permitting the adjustment of the latter for supporting and securing purposes, the upper part of the rod being equipped with a clamping plate 75 co-operating with the block for supporting the hood, substantially as described.

13. The combination with the hood of an automobile engine, of a block mounted adjacent the hood and adjustable for hood supporting purposes, and a spring actuated clamping plate located above the block and co-operating therewith, substantially as described. 80

14. The combination with the hood, of an 85 automobile engine, of a block mounted adjacent the hood and adjustable to permit the raising and lowering of the hood, a spring actuated rod passing through the block, and a clamping plate secured to the upper extremity of the rod and co-operating with the block for the purpose set forth.

15. The combination with a hood of an automobile engine, of means mounted adjacent the hood, and adjustable to bring its 95 upper and lower extremities alternately into and out of the path of the side of the hood as the latter is raised and lowered.

16. The combination, with the hood of an automobile engine, of means supported by 100 the frame work of the machine and adapted to engage the lower edge of the side of the hood for securing the latter in an elevated position, the said means bridging the space between the lower edge of the side of the 105 hood and the frame of the machine when the hood is secured in said position.

17. The combination, with the hood of an automobile engine, of means supported by the frame work of the machine and adapted to engage the side of the hood to support the latter in an elevated position, said means bridging the space between the lower edge 110 of the side of the hood and the frame of the machine when the hood is in said elevated 115 position.

18. The combination, with the hood of an automobile engine, of means movably supported by the frame work of the machine and whose opposite extremities are adapted 120 to alternately engage the side of the hood.

19. The combination, with the hood of an automobile engine, of means supported by the frame work of the machine and whose opposite extremities are adapted to alternately engage the lower edge of the side of the hood for the purpose set forth. 125

20. The combination, with the hood of an

automobile engine, of means movably supported upon opposite sides of the frame work, and the opposite extremities of each of said means adapted to alternately engage
5 the corresponding side of the hood for securing the latter in the closed position or for supporting the same in an elevated position.

In testimony whereof I affix my signature in presence of two witnesses.

WILLIS H. GUNDRUM.
